UNITED STATES PATENT OFFICE

GEORGE A. WILLIAMS, OF DECATUR, ILLINOIS, ASSIGNOR TO WILLIAMS SEALING CORPORATION, OF DECATUR, ILLINOIS, A CORPORATION OF ILLINOIS

CONTAINER NOZZLE AND CLOSURE THEREFOR

Application filed June 3, 1929. Serial No. 367,974.

This invention relates to nozzles for containers, and more particularly to the means for sealing the said nozzles. It is the general purpose and object of the invention to provide a cooperating construction of nozzle and closure means therefor which will enable the said closure means to be quickly applied to and conveniently removed from the nozzle and which, through the application of the closure means, will result in compacting the gasket forming part of such means against the end of the nozzle, thereby to provide a tight and leak-proof joint.

The invention is adapted for use with nozzles having a downwardly directed skirt within the outer body of the nozzle, such skirt usually being formed by rolling or bending the outer end of the nozzle inwardly and downwardly.

20 The invention herein is disclosed in the drawings forming part hereof wherein Fig. 1 represents a sectional view through the top of the receptacle and its nozzle and the closure means therefor; Fig. 2 a view of the nozzle and closure means similar to Fig. 1, the sectional view being taken at right angles to Fig. 1; Fig. 3 a plan view of the nozzle; Fig. 4 a bottom plan view of the closure for said nozzle; and Fig. 5 a sectional view of the 30 top of the nozzle, the section corresponding to that on which Fig. 1 is taken.

In the said drawings, 1 represents a container, preferably of sheet metal, and having thereon a nozzle comprising the body 2 and the inwardly and downwardly directed upper edge portion 3. The bead which is thus formed by such edge portion is provided at the bottom of its inner edge with a plurality of inwardly extending lugs 4 formed integral 40 with the metal of which the nozzle is composed. Two such lugs are shown, although the number may be varied as desired.

Cooperating with the aforesaid nozzle is a closure, the said closure being in the form of 45 a cap having an outer and upper annular portion 5 between which and the top of the bead there is interposed a gasket 6 of resilient compressible material, such as rubber, cork, or cork composition. The cap comprises, in 50 addition to the outer annular portion 5, a

cup 7, the outer diameter of which is such as to enable the cup to be slipped between the lugs 4 with its bottom projecting below the same. The cup is provided with a plurality of outwardly extending inclines 8 preferably struck from the metal of the cup and forming thread segments, which segments are arranged to cooperate with the lugs 4 when the closure is rotated in the appropriate direction, thereby to draw the closure downwardly and compress the gasket against the top of the nozzle. By rotating the closure in the reverse direction, it will be obvious that the thread segments will disengage the lugs and that the closure may be removed.

The construction described and shown herein is economical of production but is extremely efficient for the realization of the purposes for which it is designed.

Having thus described my invention, what I claim is:

In a device of the character described, a cylindrical nozzle having an inwardly and downwardly extending bead substantially semi-circular in vertical cross-section, the lower edge of said bead having formed integral therewith a plurality of inwardly extending lugs, each merging gradually with the edge of said bead and all lying in a plane perpendicular to the axis of said cylinder, and a cap adapted to close said nozzle, said cap having an annular gasket carrying portion, substantially cylindrical in cross-section and conforming to said bead and having an integral portion extending below and within said bead and having integral, outwardly extending, angularly disposed thread segments adapted to cooperate with said lugs for tightening said cap on said nozzle.

In testimony whereof, I hereunto affix my signature.

GEORGE A. WILLIAMS.
